ELECTRIC FORGING HAMMER

Edward Larson, Austin, Nev., assignor of one-fourth to H. F. Connelly, one-fourth to William Rast, and one-fourth to J. R. Sibbald, Austin, Nev.

Application December 26, 1935, Serial No. 56,275

1 Claim. (Cl. 172—240)

My invention relates generally to electric hammer means, and particularly to an electro-magnetically operated forging hammer, and an important object of the invention is to provide a simple, rugged, and efficient device of this character which can be produced and operated at relatively low cost.

Another important object of the invention is to provide a mechanically efficient arrangement 10 of the character indicated above in which the parts are easily accessible for repair or replacement.

Other important objects of my invention will be apparent from a reading of the following description in connection with the drawings, wherein for purposes of illustration I have shown a preferred embodiment of my invention.

In the drawings:—

Figure 1 is a general diagrammatic representation of the electric wiring and connections of the embodiment.

Figure 2 is a side elevational view of the embodiment.

Figure 3 is a transverse vertical sectional view 25 taken through Figure 2 and looking from left to right.

Figure 4 is a side elevational view of the tube and its supports and flanges.

Figure 5 is a side elevational view of the piston or core and the hammer.

Figure 6 is a transverse vertical sectional view taken through the core.

Figure 7 is a transverse vertical sectional view taken through the hammer.

Figure 8 is a plan view of the manual operating lever or switch.

Referring in detail to the drawings, the letter A generally designates the upper coil and the letter B the lower coil of the piston operating assembly. For six to eight volts operation these coils are wound with No. 10 gauge wire. These coils are wound on a brass hollow cylinder 1 in which works the piston or core 4 which is made preferably of steel tubing and has screwed into its opposite ends the solid magnetically permeable heads 2 and 3.

The lower end 3 is axially threaded to receive the upper end of the piston rod 5 whereby the piston is operatively connected to the piston 4.

The rod 5 is preferably of steel and has its lower end threaded as indicated in the top of the hammer 6 which is of steel.

The hammer operates in conjunction with the anvil 7 which is preferably a steel block and has wound thereon the coil C which is wound to

give anvil 7 the same magnetic effect as the hammer 6, so as to make the anvil neutral so that the magnetized hammer will not stick to it. The coil C is a tandem wound coil and comes into action at the same time that the coil A. 5

The numeral 9 generally designates a manually operating lever or switch lever which is pivotally mounted as indicated by the numeral 9' to a suitable support.

The numeral 10 designates the contact point 10 which is connected to the wire 15 which leads to the inside winding of the coil A, and this contact is also connected to the wire 17 which leads to the coil C.

The numeral 11 designates the contact point 15 which is connected to the wire 16 which leads to the inside winding of the coil C.

The numerals 12 and 12' designate the contact points on the lever 9 which engage respectively the contact points 10 and 11. 20

The wire 14 leads from the contact 12, 12' to the negative post on an energizing battery such as a storage battery. The wire 13 leads from the two outside windings of the coils A and B to the positive post on the battery, while the 25 wire 18 leads from the coil C to the wire 13.

Referring particularly to Figure 4, there is therein shown the brass cylinder 1 with the brass flanges 20, 21 and 22, the flanges 20 and 22 acting as brackets to fasten the coils to the 30 support 23 as shown in Figure 2 and the brass flange 21 acting as a separator between the coils A and C.

To operate the device of the invention, the lever 9 is raised so as to bring the contact points 35

12' and 10 into contact so as to cause electric current to flow from the battery through the coils A and C, thereby making the anvil neutral to the hammer and causing a strong magnetic attraction in the coil A, so as to cause the piston to be drawn upwardly into a position in which the upper end of the core or piston is above the tube. By moving the lever downwardly so as to engage the contact 12' with the contact 11, electric current is caused to flow from the battery 40 through the coil B, which causes a strong magnetic attraction, following the lapse of the attraction in the coil A, so that the piston is drawn downwardly so that the hammer is forced downwardly with a striking blow toward the anvil. 45

These operations can be performed almost as quickly as a person can manipulate the lever 9 up and down by hand.

Although I have shown and described herein a preferred embodiment of my invention, it is to be 50 55

definitely understood that I do not desire to limit the application of the invention thereto, and any change or changes may be made in the materials, and in the structure and arrangement of the parts, within the spirit of the invention and the scope of the subjoined claim.

5 What is claimed is:—

An electric hammer of the class described comprising a pair of longitudinally disposed solenoids each having an electrical winding thereon, an armature movable in said solenoids, a hammer head on said armature, an anvil for cooperation

with said hammer head, an electrical winding surrounding said anvil, a source of electrical supply, a switch, said source of electrical supply and said switch being included in circuit with the windings of the solenoids for selectively energizing said windings for effecting a reciprocating movement of said armature, and said winding of the anvil being connected in circuit with said source of supply and said switch and adapted to be energized simultaneously with the energization of one of the windings of the solenoids.

5 10 EDWARD LARSON.
